Primary Examiner — Ramzi Almatrahi(74) *Attorney, Agent, or Firm* — Justin Lampel(57) **CLAIM**

The ornamental design for an endoscope camera dual-lens, as shown and described.

DESCRIPTION

FIG. 1 is a front perspective view of an endoscope camera dual-lens showing my new design;

FIG. 2 is a back perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of portion 9 shown in FIG. 1.

The broken lines depict portions of the endoscope camera dual-lens and form no part of the claimed design.

The broken lines depict portions of the endoscope camera dual-lens that form no part of the claimed design. The dot-dash broken lines encircling an enlargement portion of the design forms no part of the claimed design.
